UNITED STATES PATENT OFFICE.

MELVILLE CLARK, OF CHICAGO, ILLINOIS.

AUTOMATIC PIANO.

No. 846,090.

Specification of Letters Patent.

Patented March 5, 1907.

Application filed December 28, 1905. Serial No. 293,157.

To all whom it may concern:

Be it known that I, MELVILLE CLARK, a citizen of the United States, residing at Chicago, in the county of Cook and State of Illinois, have invented new and useful Improvements in Automatic Pianos, of which the following is a specification, reference being had to the accompanying drawings, forming a part thereof.

10 The purpose of this invention is to provide an improved structure of interior automatic playing devices in an automatic piano and improved disposition of such devices with respect to the piano case and action, the construction being contrived for such improved disposition or arrangement.

It consists of the features of construction set out in the claims.

In the drawings, Figure 1 is a vertical fore-and-aft sectional view of a portion of a piano having the improved interior playing devices of this invention. Fig. 2 is a section at the line 2-2 on Fig. 1, the portion corresponding to the middle portion of the manual being broken out to condense the view.

25 The drawings show a piano-case of the usual construction, requiring no specific description.

The parts of the case will be referred to by 30 their customary names, so far as necessary to mention them in locating or defining the position of the parts which particularly concern the present invention. The pumbers 1 and the exhaust-air bellows or receiver 2 are 35 mounted upon opposite sides of the foundation-board 3, all being detachably secured to the under side of the key-table 4, the specific construction shown being that which is more particularly described in my Patent No. 40 795,817, August 1, 1905, involving the employment of hanger-boards 5, interposed between the foundation-board 3 below the pumbers and a board 6, which extends above the pumbers and being detachably secured 45 to the under side of the key-table serves to connect the entire bellows construction thus far described removably with the key-table below the latter.

The pneumatic-action is mounted entirely 50 above the key-table. This action comprises the customary exhaust-air chamber 8, which contains the primary pneumatics 9 for operating the valves 10, which control communication of the ducts 11, which lead to the motor-pneumatics 12, with the rarefied air of

the chamber 8 or the outer atmospheric air, the motor-pneumatics being put in communication with the rarefied air when the primary pneumatics are inflated to cause the valves to close the ports 13 and being in communication with the outer atmospheric air when the primary pneumatics are collapsed to cause the valves to seat over the ports 13^a. This action is familiar and requires no further explanation. The motor-pneumatics 60 are distributed in a plurality of banks or horizontal levels, three such banks being employed in the construction as illustrated in the drawings, thereby allowing to each motor-pneumatic a lateral space corresponding 65 to that allotted to three keys of the manual. The pneumatics in these three banks or levels are disposed in "staggered" order to permit the connections from the several pneumatics of the upper levels to the corresponding 70 manual-keys to extend between the like connections from the pneumatics of the lower levels.

The three banks or levels of motor-pneumatics are mounted, respectively, on three 80 shelves or supports 14, rigidly secured together one above another, constituting parts of a rigid frame structure, which comprises beside said shelves the front duct-board 15, top duct-board 16, and spacing-posts 17 at 85 the ends and at intervals in the length of the shelves at or near the rear edges of the latter. The duct-boards 15 and 16 contain the ducts 11 for connecting the motor-pneumatics respectively with their controlling-primaries. 90 The motor-pneumatics 12 have their moving members 12^a at the lower side, so that they move upward in the collapsing of the pneumatics. They are hinged at their forward ends, and at their rear ends they are connected each by a downwardly-extending pitman or link 18 with the rear end of the lever 19. These levers 19 extend fore and aft under the motor-pneumatic system, having their fulcrums intermediate their ends 100 supported on the rigid motor-pneumatic frame. At the forward end each lever carries a stroke-button 20, adjustably secured at the lower side of the lever overhanging the proper manual-key forward of the fulcrum of 105 the latter. The adjustable attachment of the stroke-buttons to the levers 19 is conveniently effected by mounting each of said buttons on the lower end of a screw 21, whose upper end having a slotted head is 110

accessible above the keys for adjusting the buttons to cause them to accurately touch their respective manual-keys, so that all may have equal action upon the keys without lost motion with respect to any of them and so as to be readily adjusted from time to time to compensate for any unequal compression of the felt face of the buttons or for any sagging or settling of the keys themselves or of the key-table which sometimes occur.

It will be observed that the rarefied-air chamber 8, containing the primary pneumatics and sometimes termed the "primary-pneumatic" chamber, is mounted upon the rear part of the motor-pneumatic frame—that is to say, at the rear edge of the horizontal duct-board 16. This relative arrangement of the primary-pneumatic chamber and the motor-pneumatic frame and

system of motor-pneumatics permits the introduction of the entire action within a piano-case of customary or ordinary construction, the primary-pneumatic chamber being located immediately behind the music-desk 25 and the motor-pneumatic system constituting a rectangular structure which occupies a space under the shelf or shoulder 26 below and forward of the desk and above and rearward of the manual.

It will be noticed also that the levers 19 extend forward beyond the forward side of the motor-pneumatic frame far enough to expose the heads of the screws 21 forward of the front vertical panel 27, which bounds at the forward side said shouldered portion of the case within which the motor-pneumatic system is contained. A removable strip 28 at the foot of the shouldered portion of the case immediately rearward of the manual serves to protect these screws and upon its removal to give easy access to them for adjustment.

It will be noticed that the described arrangement and location of the primary-pneumatic chamber causes the atmospheric-air ports 13 and the valves 10 to be exposed at the forward side, where the valves are readily accessible for adjustment. Also that the vents 29 for the primary pneumatics are readily made accessible at the same forward side by completing the closure of the primary-pneumatic chamber at the forward side by a removable plate 31, upon the removal of which the venting-apertures can be investigated and manipulated for the well-known purpose for which this is desirable. Every part of the pneumatic-action, therefore, requiring access for adjustment either to other parts of the pneumatic-action or to the manual-keys is accessible at the front and above the manual—that is to say, in the easiest position for doing any work necessary to be done upon these parts. The minimum degree of expertness is therefore necessary in order to keep the automatic playing devices

in order and to adjust them for any purpose for which such adjustment may become necessary.

The controlling-sheet 32, take-up and rewind rolls 33 and 34, and the operating mechanism for the rolls, together with the tracker-board 35, are mounted in their customary relation to each other at the upper part of the piano-case directly above the primary exhaust-chamber 8, and the ducts 36 36 from the tracker-board are connected to the several primary pneumatics, the portion of said ducts above the primary-pneumatic chamber being formed, as customary, of flexible tubes and disposed in any space conveniently available when extending behind the take-up roll to reach the tracker-board. The entire pneumatic-action above the manual-keys is mounted so as to be handled integrally, the frame 37, in which the tracker-board is mounted, and the take-up and rewind rolls are journaled, and on which the framework of the motor mechanism of whatever sort for rewinding the rolls is also mounted, being itself mounted rigidly upon the top of the primary-pneumatic air-chamber 8. This air-chamber has its ends extending beyond the motor-pneumatic frame structure, so as to overhang the key-table, through which pipes 38 38 extend for connecting the said chamber 8 with the receiver 2, mounted, as described, below the key-table, connecting-passages being made through the hanger-boards 5, which extend, as described, from the foundation-board 3 to the key-table.

I claim—

1. In an automatic piano, in combination with the piano-case and the manual-keys, a pneumatic-action comprising motor-pneumatics and their controlling and operating devices contained in the piano-case, such motor-pneumatics being extended horizontally above the rear portion of the manual-keys within the case, having their moving members at their lower side and hinged at their forward ends for lifting at their rear ends in the collapse of the pneumatics; levers fulcrumed upon the lower side of the motor-pneumatic-supporting frame extending fore and aft underneath the latter; operating connections from the rear ends of such levers to the rear ends of the motor-pneumatics respectively, said levers at their forward ends overhanging and being adapted to act downwardly upon the respective keys of the manual forward of the fulcrums of the latter.

2. In an automatic piano, in combination with the piano-case and the manual-keys, a pneumatic-action comprising motor-pneumatics and their controlling and operating devices contained in the piano-case, such motor-pneumatics being extended horizontally above the rear portion of the manual-keys within the case, having their moving

members at their lower side and hinged at their forward ends for lifting at their rear ends in the collapse of the pneumatics; levers fulcrumed upon the lower side of the motor-pneumatic-supporting frame extending fore and aft underneath the latter; operating connections from the rear ends of such levers to the rear ends of the motor-pneumatics respectively; striker-buttons adjustably mounted on the forward ends of said levers overhanging the respective keys of the manual forward of the fulcrums of the latter.

3. In an automatic piano, in combination with the piano-case and the manual-keys, a pneumatic-action comprising motor-pneumatics and their controlling and operating devices contained in the piano-case, such motor-pneumatics being extended horizontally above the rear portion of the manual-keys within the case, having their moving members at their lower side and hinged at their forward ends for lifting at their rear ends in the collapse of the pneumatics; levers fulcrumed upon the lower side of the motor-pneumatic-supporting frame extending fore and aft underneath the latter; operating connections from the rear ends of such levers to the rear ends of the motor-pneumatics respectively; striker-buttons having threaded stems set through the forward ends of the levers with the buttons at the lower end of the stems overhanging the respective keys of the manual forward of the fulcrums of the latter, the upper ends of the stems being upwardly accessible for adjustment of the buttons.

4. In an automatic piano, in combination with the piano-case having back of the manual an elevated or shouldered portion in-

closed at the upper and forward side, and having the music-desk extending up from the rear of the shelf formed by the upper side of said shouldered portion, a pneumatic-action comprising a system of motor-pneumatics housed within said shouldered portion and having a supporting-frame which at the upper side protrudes inwardly beyond the lower end of the desk; a primary-pneumatic chamber mounted upon said rearwardly-protruding portion of the motor-pneumatic frame and extending upwardly therefrom behind the desk, the motor-pneumatics of said system having their moving members located at the lower side and hinged at the forward end for lifting at the rear ends in the collapse of the pneumatics; fore-and-aft extending levers fulcrumed intermediate their ends on the lower side of the motor-pneumatic frame; connections from the moving members of the pneumatics to the rear ends of said levers respectively, said levers being extended forwardly beyond the lower edge of the forward inclosing side of said shouldered portion of the case and adapted to be exposed upwardly at said forward ends, and strikers mounted on said upwardly-exposed ends overhanging the manual-keys respectively forward of the fulcrums of the latter.

In testimony whereof I have hereunto set my hand, in the presence of two witnesses, at Chicago, Illinois, this 20th day of December, 1905.

MELVILLE CLARK.
